UNITED STATES PATENT OFFICE.

JOHN WALDHEIM, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,416,428.

Specification of Letters Patent. Patented May 16, 1922.

Application filed May 27, 1919. Serial No. 300,067.

To all whom it may concern:

Be it known that I, JOHN WALDHEIM, a citizen of the United States, residing in Elizabeth, in the county of Union and State 5 of New Jersey, have invented certain new and useful Improvements in Combined Typewriting and Computing Machines, of which the following is a specification.

This invention is illustrated as applied to 10 a combined typewriting and computing machine which may be like that shown in the application of Henry L. Pitman, No. 198,375, filed October 25, 1917 (now Patent No. 1,350,387, dated August 24, 1920), in which a 15 sub-carriage or cross-computer carriage is adapted to travel intermittently with the typewriter carriage during the letter-feeding movements of the latter. In other words, the computer-carriage is picked up 20 every time the carriage passes into a computing zone, and becomes released from the typewriter carriage as it passes out of the computing zone.

The typewriter carriage is sometimes re- 25 positioned in a computing zone, for example when making corrections. When this is done under ordinary conditions, it is necessary to move the carriage back beyond the computing zone, in order to pick up the 30 cross-computer carriage, and then move the typewriter carriage forwardly to the denominational position in the computing zone.

In the Pitman application above referred to, means is provided by which the cross- 35 computer carriage may be connected with the typewriter carriage by means of a key in the keyboard after the typewriter carriage has been moved back into the computing zone.

40 An object of this invention is to provide means to reconnect the cross-computer carriage or sub-carriage with the typewriter carriage by means actuated directly by the typewriter carriage when the latter is moved 45 back into the computing zone.

In carrying out the invention, pick-up devices, located in the columnar positions of the typewriter carriage, may engage to actuate a cam member when the carriage is 50 moved back. The cam member forms part of a connection, which extends from the cross-computer carriage, and, when actuated, is effective to reconnect the computer

carriage by means of a pick-up hook, which is adapted to engage with any one of the 55 pick-up devices.

Means is provided whereby the cam member may be rendered ineffective when the typewriter carriage is returned to the beginning of a new line, so as to avoid unnecessary reciprocations of the cross-computer carriage during the return movement of the typewriter carriage. Provision is also made to again render the cam member effective when the carriage moves in a letter-space direction before the first pick-up device reaches the computing zone, so that the cam member may again be actuated by moving back the carriage after it has again passed through a computing zone in a letter- 70 feed direction.

Other features and advantages will hereinafter appear.

In the accompanying drawings, Figure 1 is a rear view of the upper part 75 of the machine, and shows the typewriter carriage and the cross-computer carriage traveling through a computing zone.

Figure 2 is a similar view and shows the parts in position after the carriage has 80 passed out of the computing zone with the cross-computer carriage returned to its normal position.

Figure 3 is a view similar to Figure 2, and shows the parts in position when the 85 typewriter carriage is backed into the computing zone, the cam member being actuated by the pick-up device and the pick-up hook reconnected with the pick-up device.

Figure 4 is a fragmentary sectional side 90 view taken on the line 4-4 of Figure 1, and looking in the direction of the arrows at said line.

Figure 5 is a detail perspective view, as seen from the back, of a lever on which the 95 cam member is supported, and shows a shifter which may be engaged by the pick-up devices to render the cam member ineffective.

Figure 6 is a skeleton perspective view of 100 the machine, as seen from the front and upper left-hand corner.

Figure 7 is a detail view, showing the construction of one of the pick-up devices and the cam member.

Figure 8 is a detail rear view of the 105

pivoted lever with the shifter and the cam member carried thereby, and shows the shifter actuated by one of the pick-up devices to move the cam member out of effective relation with the pick-up devices.

Figure 9 is a detail perspective view of the parts which constitute the shifter.

Numeral keys (not shown) swing type-bars 10 upwardly and rearwardly to cause 10 types 11 to strike against the front side of a platen 12 (Figure 6) rotatively supported on a carriage 13. The carriage is urged in a letter-feeding direction by a spring-drum 14 (Figure 1) connected to said carriage by 15 a strap 15. The letter-feeding movements of the carriage may be controlled by escapement devices (not shown), which may be like those used in the Underwood machine.

The carriage may be rapidly positioned 20 denominationally in any one of a plurality of columns by key-actuated denominational stops 16 (Figures 4 and 6), which are adapted to release the carriage and engage with column-stops 17 to arrest the carriage in the 25 proper position.

The numeral keys are adapted to actuate a master wheel 18 through various distances, the extent of rotation being proportional to the values of the numeral keys. Column-to- 30 talizers 20 are adjustably supported on a bar 21 mounted to travel on a fixed rail or guide bar 22 and with the carriage, so that, as the carriage passes through a computing zone, computing wheels 23 are brought seriatim 35 into effective relation with the master wheel 18. The column-totalizers 20 may be adjusted in positions corresponding with the positions of the column-stops 17, so that any one of them may be rapidly positioned relatively to the master wheel by the denominational 40 stops 16.

A cross-totalizer 24 is provided so that computation may be had crosswise of the various columns. The cross-totalizer is 45 adapted to travel intermittently with the carriage (in a manner which will be presently described) to bring computing wheels 25 seriatim into effective relation with a master wheel 26. The master wheel 26, for 50 the cross-totalizer 24, may be connected with the master wheel 18 for the column-totalizers, so as to rotate in unison therewith. For this purpose, the master wheel 18 is connected with a horizontal shaft 27, which drives a 55 vertical shaft 28 through a pair of bevel gears 30 and 31. The vertical shaft 28 in turn drives a horizontal shaft 32 through bevel gears 33 and 34, the horizontal shaft being connected with the master wheel 26.

60 The cross-totalizer is supported on a traveling bar or cross-computer carriage 35 guided on a fixed rail or guide bar 36.

To cause the cross-totalizer 24 to travel intermittently with the typewriter carriage 65 13, there is set at each column-stop 17 a pick-

up element 37. As the carriage enters the computing zone, the nearest pick-up element engages with a hook 38 on a pick-up bar 39 pivotally connected at 40 to a rack 41, to move the latter rightwardly (Figure 1). 70 The rack actuates a double sector member 42 to rotate the pinion 43 secured to a shaft 44 extending from the back to the front of the machine (Figure 6), where it is provided with another pinion 45 engaging with a rack 75 46 on the cross-computer carriage to move the latter step by step relatively to the master wheel 26 as the numbers are typed while the carriage 13 is in the computing zone. As the carriage passes out of the computing 80 zone, the pick-up bar becomes released from the pick-up element by a pin 47 on the pick-up bar 39, which engages a cam 48, on a fixed plate 50. The pick-up bar is swung about its pivot 40, thus freeing the hook 38 85 of the pick-up element and permitting the pick-up bar 39 to be restored to its normal position (Figure 2) by a return spring 51 coiled about the shaft 44, which connects the double sector member 42 with the rack 46 90 95 on the cross-computer carriage. Thus, the spring 51 also returns the cross-totalizer 24 to its normal position at the right of the master wheel 26. The hook 38 on the pick-up bar may be held in the path of the pick-up elements 37 by a spring-controlled lever 52, having a stud 53 thereon bearing against the under side of the pick-up bar 39.

The column-stops 17 and the pick-up elements 37, of which there may be one of each for each letter-space position, may be selectively set by a key in the keyboard, as in the Pitman application above referred to, and may be held in their ineffective and effective 100 positions by detents 54 and 55. 105

To reposition the cross-totalizer relatively to the master wheel and reconnect it with the typewriter carriage when the latter is moved back into the computing zone, the pick-up elements 37 are adapted to engage 110 a cam 56 (Figure 2) on a cam member 57, to move the latter upwardly to swing a lever 58 about its pivot 59, to pull upwardly a link 60 which is connected at its lower end to an arm 61 extending from a shaft 115 62, so that the latter may be rocked thereby. The shaft 62 has extending forwardly therefrom another arm 63, which pulls downwardly on a link 64, to rock a bell-crank 65 about its pivot 66 to reposition 120 the cross-totalizer 24 relatively to the master wheel 26, by pulling it leftwardly (Figure 6) by a connecting link 67. While the cross-totalizer is being repositioned, the pick-up bar 39 is also advanced toward the 125 pick-up element to reconnect it therewith, while the pick-up element on the carriage is being moved back into the computing zone. This advancing movement of the pick-up bar 39 is effected through the connection, herein- 130

before described, including the horizontal shaft 44 extending rearwardly from the rack bar 46 on the cross-computer carriage or sub-carriage 35.

- 5 The cam member 57 is pivotally mounted on a pin 68 on the lever 58 and is provided with another cam 70 at its lower end (Figures 5 and 7), so that it may be swung to one side by the various pick-up elements as they 10 pass it when the carriage moves in a letter-feed direction. A leaf spring 71 is provided to return the cam member 57 to its normal effective position each time a pick-up element has passed it. It should be understood that 15 the detents 55 are strong enough to prevent displacement of the pick-up elements by the leaf spring 71. The pick-up elements 37 are beveled at 69 (Figures 5 and 7) to facilitate their engagement with the cam 70 on the 20 cam member 57.

It is desirable to render the cam member 57 ineffective, so as to avoid unnecessary reciprocations of the cross-totalizer 24 as the 25 various pick-up elements 37 move past said cam member when the typewriter carriage is returned to the beginning of a new line. For this purpose, there is provided a shifter 72 comprising an arm 73 and two actuating or operating members 74 and 75 (Figures 5 30 and 9) pivotally mounted on a headed stud 76. When the carriage leaves the computing zone on its return movement, the nearest pick-up element 37 engages with the actuating member 74 to rock the arm 73 about its pivot through the medium of a pin 77 with which the arm engages. The upper end of the arm 73 is provided with a stud 78 engaging in a cam slot 80 of an intermediate lever 81, to swing the latter about 35 its pivot 82 and cause its opposite end to move upwardly to move the cam member 57 therewith to withdraw it from effective relation with the pick-up members 37 (Figure 8); the cam member 57 being connected 40 with the intermediate lever by a pin 83 projecting into a slot 84 formed in the lever 81. As the carriage continues to move backwardly, the pick-up members 37 engage with the operating member 75, which, in 45 the meantime, has been moved into effective relation with the pick-up members (Figure 8), and swings the operating member idly about its pivot and against the tension of a spring 85 (Figures 1 and 9) connected between the two actuating members 74 and 75, which normally holds said members against 50 the stud 77 on the arm 73. When the carriage is again advanced in a letter-feeding direction (rightwardly in Figure 8) the 55 nearest pick-up member 37 engages with the actuating member 75 to swing the shifter 72 about the stud 76 and actuate the intermediate lever 81 to lower the cam member 57 into effective relation with the pick-up 60 members 37. This occurs prior to the en-

trance of the carriage into the computing zone. To permit up-and-down movement of the cam member 57, it is provided with a slot 86 through which the pivot stud 68 passes. The stud is held in ears 87 on the 70 lever 58 which may be broad enough to prevent any wiggling of the cam member on the lever 58.

Variations may be resorted to within the scope of the invention, and portions of the 75 improvements may be used without others.

Having thus described my invention, I claim:

1. In a combined typewriting and computing machine, the combination of a letter-feeding carriage, a computer carriage adapted to be connected to travel with said letter-feeding carriage through a computing zone, means to release said computer carriage when the letter-feeding carriage passes 80 out of the computing zone, and means actuatable by said letter-feeding carriage to effect a reconnection of said computer carriage with the letter-feeding carriage when the latter is moved back into the computing 85 zone.

2. In a combined typewriting and computing machine, the combination of a letter-feeding carriage, a computer carriage to travel with said letter-feeding carriage 90 through a series of denominational positions in a computing zone, means to release said computer carriage when the letter-feeding carriage passes out of the computing zone, and means actuatable by said letter-feeding 95 carriage to reconnect said computer carriage with the letter-feeding carriage when the latter is moved back to any denominational position in the computing zone.

3. In a combined typewriting and computing machine, the combination of a letter-feeding carriage, a column computer unit having an element to travel with said carriage through a computing zone, and a co-operative element; a cross-computer unit 105 having an element to be connected to travel with said carriage through the computing zone, and a co-operative element; means to release the traveling cross-computer element when the carriage passes out of the computing zone; and means actuatable by said carriage to reconnect the traveling cross-computer element with the carriage and reposition it relatively to its co-operative element 110 when the carriage is moved back into the 115 computing zone.

4. In a combined typewriting and computing machine, the combination of a letter-feeding carriage, a totalizer to travel with said carriage through a computing zone, a second totalizer adapted to be connected to travel with said carriage through the computing zone, means to release the second-named totalizer when the carriage passes 125 out of the computing zone, and means actu- 130

able by said carriage to effect the reconnection of the second-named totalizer with the carriage when the latter is moved back into the computing zone.

5 5. In a combined typewriting and computing machine, the combination of a letter-feeding carriage, a computer carriage to travel with said letter-feeding carriage through a computing zone, means to release 70
10 said computer carriage when the letter-feeding carriage passes out of the computing zone, a train of mechanism comprising a cam member connected with said computer carriage, and means on said carriage to actuate 75
15 said cam member to reconnect said computer carriage when said letter-feeding carriage is moved back into the computing zone.

6. In a combined typewriting and computing machine, the combination of a letter-feeding carriage, a computer carriage, pick-up devices to cause said computer carriage to travel intermittently with said letter-feeding carriage, and means engageable by 80
20 said pick-up devices when the letter-feeding carriage is backed into a computing zone to reposition the computer carriage relatively 85
25 to the letter-feeding carriage and to reconnect it therewith.

30 7. In a combined typewriting and computing machine, the combination of a letter-feeding carriage, a computer carriage, adjustable devices on the letter-feeding carriage, means engageable by said devices to 90
35 cause the computer carriage to travel intermittently with the letter-feeding carriage through a computing zone, means engageable by said devices when the letter-feeding carriage is backed into the computing zone
40 to reconnect said computer carriage with said letter-feeding carriage, and a controlling device engageable by said adjustable devices to render the second-mentioned means ineffective when the letter-feeding carriage
45 is backed beyond the computing zone.

8. In a combined typewriting and computing machine, the combination of a letter-feeding carriage, a plurality of totalizers to travel with said carriage through a computing zone, a cross-totalizer adapted to be connected to travel intermittently with said carriage through the computing zone, means to release said last-named totalizer when the carriage passes out of the computing zone, 100
50 means to reconnect said totalizer with the carriage when the latter is moved back into the computing zone, and means to render said reconnecting means ineffective when the carriage is backed beyond said computing
55 zone.

9. In a combined typewriting and computing machine, the combination of a letter-feeding carriage, pick-up devices to travel with said carriage, a computer carriage 105
60 adapted to be picked up by said devices, so

as to cause the computer carriage to travel intermittently with said letter-feeding carriage through a computing zone, means to release the computer carriage when the letter-feeding carriage passes out of the computing zone, means to reconnect said computer carriage with the carriage when the latter is moved back into the computing zone, and a shifter to render the reconnecting means ineffective when the carriage is 110
70 moved beyond the computing zone.

10. In a combined typewriting and computing machine, the combination of a letter-feeding carriage, pick-up devices to travel with said carriage, a computer carriage 115
80 adapted to be picked up by said devices, so as to cause the computer carriage to travel intermittently with said letter-feeding carriage through a computing zone, means to release the computer carriage when the letter-feeding carriage passes out of the computing zone, means to reconnect said computer carriage with the carriage when the latter is moved back into the computing zone, and a shifter to render the reconnecting means ineffective when the carriage is 120
85 moved back beyond the computing zone, so that the devices may pass the reconnecting means without actuating the same, the nearest device being effective to actuate the 90
95 shifter when the letter-feeding carriage is again moved in a letter-feed direction, so as to render the reconnecting means effective.

11. In a combined typewriting and computing machine, the combination of a letter-feeding carriage, pick-up devices to travel with said carriage through a computing zone, a computer carriage adapted to be picked up by said devices, so as to cause the 100
105 computer carriage to travel intermittently with said letter-feeding carriage through the computing zone, means to release the computer carriage when the letter-feeding carriage passes out of the computing zone, 110
110 a pivoted lever, means connecting said pivoted lever with said computer carriage, a member on said lever to be engaged by any one of said devices to reconnect the computer carriage with the letter-feeding carriage when the latter is backed into the computing zone.

12. In a combined typewriting and computing machine, the combination of a letter-feeding carriage, pick-up devices to travel 120
125 with said carriage, a computer carriage adapted to be picked up by said devices, so as to cause the computer carriage to travel intermittently with said letter-feeding carriage through a computing zone, means to release the computer carriage when the letter-feeding carriage passes out of the computing zone, a pivoted lever, a member on said lever, means connecting said pivoted lever with said computer carriage, and a 130
130

shifter on said lever, said shifter being connected with the member on said lever, said shifter being adapted to be engaged by said devices to render said member ineffective 5 when the letter-feeding carriage is backed beyond the zone.

13. In a combined typewriting and computing machine, the combination of a letter-feeding carriage, a totalizer, devices on said carriage to cause said totalizer to travel intermittently with said carriage, means comprising an element in the path of said devices to be engaged by said devices to reconnect the totalizer with the carriage when the 15 carriage is moved back into a computing zone, a shifter engageable by said devices, to render said element ineffective, an intermediate member connected with said element, said intermediate member having a 20 cam slot therein, and a stud on said shifter which engages in the cam slot of the intermediate member to shift said element.

14. In a combined typewriting and computing machine, the combination of a carriage adapted to move in a letter-feed direction, a plurality of totalizers to travel with said carriage through a computing zone, a cross-totalizer adapted to be connected to travel with said carriage at various 25 intervals through the computing zone, means to release said cross-totalizer when the carriage passes out of the computing zone, means to reconnect said cross-totalizer with the carriage when the latter is moved back into the computing zone, means to render 30 reconnecting means ineffective when the carriage is backed beyond said computing zone, and means to render said reconnecting means effective when the carriage is again moved in a letter-feed direction into the computing zone.

15. In a combined typewriting and computing machine, the combination of a carriage, a totalizer, devices on said carriage 45 to cause said totalizer to travel intermittently with said carriage, and means comprising an element in the path of said devices to be engaged by said devices to reconnect the totalizer with the carriage when the carriage is moved back into a computing zone, said element being so constructed that 50 said devices may move idly past said element when the carriage is moved in a letter-feed direction.

16. In a combined typewriting and computing machine, the combination of a carriage, a totalizer, devices on said carriage to cause said totalizer to travel intermittently with said carriage, means comprising an element in the path of said devices to be engaged by said devices to reconnect the totalizer with the carriage when the carriage is moved back into a computing zone, and a cam on said element with which said devices 65 may engage to swing said element, so that

said devices may move idly past said element when the carriage is moved in a letter-feed direction.

17. The combination of a main carriage to travel forwardly in a letter-feed direction, 70 a sub-carriage to travel with said main carriage, means to release said sub-carriage at predetermined positions in the travel of said main carriage, and means actuatable by said main carriage to move said sub-carriage and 75 reconnect it with the main carriage when the latter is moved in a reverse letter-feed direction.

18. The combination with a main carriage which may carry a work-sheet, means to 80 determine zones on the work-sheet, and typing devices to type in such zones on the work-sheet, of a sub-carriage to be connected to travel with said main carriage while any one of the zones is traveling past the printing point, means to release said sub-carriage when the main carriage is fed sufficiently to carry a zone on the work-sheet past the printing point of the typing devices, and means actuatable by said main carriage to reconnect said sub-carriage with the main carriage when the latter is moved to bring a zone on the work-sheet, carried past the printing point, back to the same. 85

19. The combination of a letter-feeding 90 carriage, a sub-carriage adapted to travel at various intervals with the letter-feeding carriage through a zone, means to reconnect the sub-carriage with the letter-feeding carriage when the latter is moved back into the zone, 100 and means to prevent unnecessary reciprocations of the sub-carriage when the letter-feeding carriage is moved back to the beginning of a new line.

20. In a combined typewriting and computing machine, in combination, a letter-feeding carriage, a computing carriage adapted to be connected to said letter-feeding carriage to travel therewith through a computing zone, means to release said computing carriage when the letter-feeding carriage passes out of the computing zone, and means, actuatable by the letter-feeding carriage, whereby, upon movement of the latter back into the computing zone, said computer carriage will be reconnected with the letter-feeding carriage. 105 110 115

21. In a combined typewriting and computing machine, in combination, a letter-feeding carriage, a cross-computer unit having an element to be connected to travel with said carriage through a computing zone and a co-operative element, means to release the traveling cross-computing element when the carriage passes out of the computing 120 125 zone, and means actuatable by the letter-feeding carriage whereby movement of the latter back into the computing zone will cause the traveling cross-computing element to be reconnected with the carriage. 130

22. In a combined typewriting and computing machine, in combination, a letter-feeding carriage, a computer carriage, connecting means whereby said computer carriage may be connected to said letter-feeding carriage to travel therewith through a computing zone, means to release said connecting means where the letter-feeding carriage passes out of the computing zone, and 10 reconnecting means whereby, upon moving said letter-feeding carriage back into the computing zone, said computer carriage will be reconnected with said letter-feeding carriage, said reconnecting means including a 15 member by which it is thrown into operation when said member is engaged by the carriage.

23. In a combined typewriting and computing machine, in combination, a letter-feeding carriage, a computer carriage, means to pick up said computer carriage and cause it to travel with said letter-feeding carriage when the latter is passing through different computing zones, means to release said computer carriage each time the letter-feeding carriage moves out of a computing zone, and means actuatable by the letter-feeding carriage whereby, upon movement of the latter back into the zone last vacated, the computer carriage will be repositioned with reference to the letter-feeding carriage and reconnected therewith.

24. In a combined typewriting and computing machine, in combination, a letter-feeding carriage, a computer carriage, means to pick up said computer carriage and cause it to travel with said letter-feeding carriage when the latter is passing through different computing zones, means to release said computer carriage each time the letter-feeding carriage moves out of a computing zone, means whereby, upon movement of the letter-feeding carriage back into the zone last vacated, the computer carriage will be re-

positioned with reference to the letter-feeding carriage and reconnected therewith, and means to render said reconnecting means ineffective when the letter-feeding carriage is backed beyond the zone in which reconnection was effected. 45 50

25. In a combined typewriting and computing machine, in combination, a letter-feeding carriage, a computer carriage, means to pick up said computer carriage and cause it to travel with said letter-feeding carriage 55 when the latter is passing through different computing zones, means to release said computer carriage each time the letter-feeding carriage moves out of a computing zone, means whereby, upon movement of the letter-feeding carriage back into the zone last vacated, the computer carriage will be repositioned with reference to the letter-feeding carriage, and reconnected therewith, means to render said reconnecting means ineffective 60 65 when the letter-feeding carriage is backed beyond the zone in which reconnection was effected, and means whereby, upon again advancing the letter-feeding carriage into a computing zone, the reconnecting means 70 will be restored to effective position.

26. The combination of a main carriage normally advancing in a letter-feed direction, a sub-carriage to travel with said main carriage, means to release said sub-carriage 75 at predetermined positions, and means actuatable by the main carriage whereby said sub-carriage will be reconnected with the main carriage when the latter is moved in a reverse letter-feed direction into a position in 80 which it would be connected with the sub-carriage when moving in the letter-feed direction.

JOHN WALDHEIM.
